UNITED STATES PATENT OFFICE

EARL W. DODDRIDGE, OF MILTON, INDIANA

AUTOMATIC GRAVE COVER

Application filed April 16, 1927. Serial No. 184,398.

The object of this invention, broadly speaking, is to provide an automatic grave-cover to be employed during the interment of a human body, and immediately prior and 5 subsequent thereto, the same being strong and durable in construction, neat and attractive in appearance, automatic and positive in its operations, easily disassembled by which it will occupy a minimum of space for storage or transportation, and which can be manufactured and sold at a comparatively low price.

More specifically stated, my object is to provide a normally horizontal grave-cover, which will cover the grave before and during the time a casket is placed thereover, preparatory to the casket being lowered into the grave. To provide means whereby as the casket starts to move downward and is being lowered into the grave, the cover will slowly open downward by gravity, finally attaining a substantially vertical position but without contact with the casket, and when the casket has moved downward to such position as not to interfere with the raising of the cover, then the cover will be slowly raised back to its normal horizontal position, thereby closing the grave, with the casket continuing to move downward until it reaches the bottom of the grave, or is otherwise retarded.

Other objects and particular advantages of my invention will become apparent in the course of the following description, and will 35 particularly suggest themselves to morticians, and to others familiar with the art to which the invention pertains.

The means for carrying out the construction and the various operations incident to 40 my invention is shown in the accompanying two-sheets of drawings, in which—Figure 1 is a top plan view of my construction in operative position over a grave, but prior to its being covered by a decorative blanket or 45 the placing of a burial casket thereover, and also showing an ordinary casket lowering device in operative position in connection with my device. Figure 2 shows an end elevation of my device in operative position 50 with relation to a grave and a lowering de-

vice, and showing a casket supported over the grave by the lowering device. Figure 3 is the same as Fig. 2, except that the casket is shown as partly lowered into the grave, and showing my device in the position it 55 would assume with the casket in the position shown. Figure 4 is a perspective detail, showing a portion of one of the wings, with a portion of an imitation-grass blanket thereon. Figure 5 is a detail view, showing 60 the first position of the rope of the pulley mechanism at one corner of the device. Figure 6 is the same except that it shows the second position. And Figure 7 is the same except that it shows the third position of 65 the same.

Similar indices denote like parts throughout the several views of the drawings.

In order that the construction, the operation, and the several advantages of my invention may be more fully understood and appreciated, I will now take up a detailed description thereof, in which I will set forth the same as comprehensively as I may.

In the drawings letter A denotes a portion 75 of an open grave having vertical sides as shown. Letter B denotes the surface of the ground in which the grave is formed.

Letters C and D denote the side or long running-boards; and E and F denote the 80 end or short running-boards.

The said four running-boards form a frame surrounding the grave and resting flat on the surface B of the ground. Letter G denotes a burial casket which is adapted 85 to fit loosely in the grave A.

The casket lowering device comprises the four corner posts H, which are adapted to rest on the boards E and F, and they are all connected by the two long rollers I and the 90 two short rollers J.

The rollers I are adapted to revolve, and they are geared to rotate together in directions opposite to each other, and the turning thereof is adapted to be controlled by the 95 handle K, which is connected with the mechanism L, only part of which is shown. Letters M and N denote the two casket supporting straps, the ends thereof being secured each to two rollers I, around which 100

they are adapted to wind, or to unwind therefrom, the two operating synchronously.

All of said parts, which are designated by letters, are old and I make no claim thereto per se, and as their constructions are well known therefore further description thereof would add more to prolixity than to clearness of comprehension.

The invention proper comprises two, oppositely disposed, wings each consisting of a central or main member, and a minor or end member located at each end of the main members, as spaced therefrom, for the purpose hereinafter stated. As the two wings are identical with each other, therefore the corresponding parts of each wing will be designated by like numerals, and a description of one will, therefore, answer for both.

Each of said wings consists of a main shaft 4, which is revolvably mounted in the hangers 1, 2 and 3, which hangers are detachably secured to the running-board C (or D) and extend inward whereby the shaft 4 is located over the edge of the grave and parallel therewith, and also they are parallel with the running-board C and D.

The main member of each wing is formed, in addition to the shaft 4, as follows: Connected with the shaft 4 are the T-fittings 5 and 6, which are located near the respective straps M and N, that is near the inner edges thereof. Secured in said fittings 5 and 6 are the end arms 7 and 8, respectively. Said arms 7 and 8 are located at right angles to the shaft 4. L-shaped fittings 9 and 10 are attached to the inner ends of the respective arms 7 and 8 and they are connected by the rod 11, which is parallel with the shaft 4. The length of the arms 7 and 8 are such that the rods 11 of the two wings are located near but not in contact with each other, in fact they should be spaced a short distance apart, as shown.

Each of the four minor wing-members, which are identical with each other consists of a T-fitting 12 secured to the shaft 4, and an L-fitting 13 secured on the end of said shaft. Extending centerward from the respective fittings 12 and 13 are the arms 14 and 15, which are of the same length as are the arms 7 and 8.

Secured on the inner ends of the arms 14 and 15 are the L-shaped fittings 16 and 17, respectively, which are connected by the rod 18.

Extending across, and connecting the arms 14 and 15, is an adjustable bar 19, which is adapted to be secured at any point desired between the shaft 4 and the rod 18.

Secured in the center of the bar 19 is an eye-bolt 20, to which is connected the pulley 21.

Secured to and extending around the roller I is a fixed collar 22. Spaced from the collar 22 and loosely surrounding the roller I is the

movable collar 23. Numeral 24 denotes a cable, or the like, one end of which is secured to the collar 22, after which it is then coiled around the roller I, then run through the pulley 21, and with its other end secured to the collar 23.

The cross-bar 19, the eye-bolt 20, the pulley 21, the collars 22 and 23, and the cable 24 constitute the pulley mechanism, of which there are four, there being two for each wing, and they provide the novel means whereby the wings are automatically lowered and raised synchronously, and in proper time, as hereinafter set forth.

The timing of the movements of the wings is accomplished by either one, or all, of the following instrumentalities: The position of the collar 22, circumferentially, upon the roller I; the number of coils of the cable around the roller I; and the position of the bar 19 along the arms 14 and 15.

By the arrangement of the cable mechanism, as shown, it will be seen, with the parts arranged as in Fig. 1, that if the roller I be revolved inwardly, that is in the direction to loosen the straps M and N, that the cables 24 will be unwound from the rollers I, thereby permitting the wings to turn downwardly gravitationally until they have come to vertical position, or nearly so, at which time all of the coils being unwound from the rollers I, then as the rollers I continue to revolve in the same direction as before, therefore the cables will then commence to wind in the opposite direction upon said rollers, thereby drawing the wings upward, that is back to horizontal or normal position, that is to their starting position shown in Figs. 1 and 2.

It will now be apparent that by this arrangement the wings will be given two directly opposite movements, with the rollers I all the while turning in one direction.

In actual practice each of the wings should each separately be covered by a blanket 25 as of artificial grass, the same being detachably secured to said wings and extending out over the running-boards around the grave, with slots formed in the blankets for the straps M and N to operate in, whereby the open grave will not be seen by persons attending an interment.

After the grave is formed the running-boards are then placed therearound as shown. Next my device is placed in position, as in Fig. 1. The blankets are then placed over my device. The lowering device is then placed in position, as shown, after which the casket may be placed upon the straps M and N, where it will be retained in suspension, as shown in Fig. 2.

Now by turning the handle K the lowering device will be caused to permit the weight of the casket to turn the rollers I, unwinding the straps M and N from said rollers.

The turning of the rollers I will unwind

the cables 24, whereby as the casket moves downward the wings of my device will turn slowly downward in advance of the casket, finally assuming vertical position, or nearly so. As soon as the casket has been lowered to where the wings will not interfere therewith then the wings will start to move upward, finally coming back to their former horizontal position at the same time that the casket reaches the bottom of the grave, or nearly so.

By the above it will be seen that the grave will be covered and closed by the time the casket reaches the lower part of the grave, and the interior of the grave will not be seen by those in attendance, and the casket will not be seen after it has moved some distance into the grave.

The position of the collar 22 and the cable 24 at the commencement of the first operation, that is with the wings as in Fig. 2, is shown in Fig. 5. The position of said parts when the wings are as in Fig. 3 is shown in Fig. 6. And the position of said parts when the wings have been returned to horizontal position is shown in Fig. 7.

The particularly novel feature of this invention resides in the fact that the wings, which are controlled by the rollers I, move first slowly downward from horizontal to vertical position, then remain stationary for an interval, and then move slowly upwardly, returning to their former horizontal position; all of which is done with the rollers I revolving continuously in one direction, and at a uniform rate of speed.

After the interment services have terminated, and those in attendance have withdrawn, then the lowering device and my device may be removed and packed into a comparatively small space, for transportation and storage until again required.

Having now fully shown and described my invention, what I claim and desire to secure by Letters Patent of the United States, is—

1. An automatic grave cover to be employed with a grave with a casket lowering device having a roller located on each side of the grave with straps connecting said rollers and wound thereon and adapted to support a casket over the grave; a pair of wings hinged whereby they may turn down into said grave, cables connecting said rollers and said wings and wound around said rollers whereby as said rollers revolve to lower the casket the said wings will turn downward until the casket has passed them, after which the wings will move upward to closed position as the casket continues to move downward to its final position in the grave.

2. A device to be used with a grave and a lowering device having a roller located on each side of said grave with straps connecting said rollers and adapted to support a

casket over said grave; an automatically operable cover normally closing the top of said grave and located below said casket, said cover comprising hinged wings, flexible means connecting said rollers to said wings providing means whereby the turning of said rollers in one direction will cause said wings to swing first in one direction and then swing back in the opposite direction with the casket moving continuously in one direction.

3. In combination with two side rollers of a lowering device, a pair of wings each consisting of a major or central portion and two end portions, with the three portions of each wing rigidly connected together, a pulley mechanism connected with each end portion of each wing, each of said pulley mechanisms comprising a cross-bar adjustably connected to its wing portion, a pulley connected to the cross-bar, a fixed collar on the roller, a loose collar surrounding the roller, a cable secured at one end to the fixed collar and adapted to coil around the roller to be wound thereon or be unwound therefrom as the roller revolves, with the other end of said cable attached to the loose collar.

4. A grave cover comprising a pair of spaced apart rotatable shafts, hangers for said shafts, a wing secured to each shaft, said wings being adapted to approach near to each other when they are located horizontally, and automatically operable means for causing said wings to turn downwardly into vertical position and then be returned to said horizontal position by the revolving of said shafts continuously in one direction.

5. An automatic grave cover comprising a pair of wings hinged on opposite edges thereof, cables connecting said wings to rollers and adapted to be wound and unwound with relation to said rollers whereby as the rollers revolve continuously in one direction the said wings will be caused to swing downward from horizontal to vertical positions and then to swing upwardly to horizontal position, substantially as set forth.

In testimony whereof I have hereunto subscribed my name.

EARL W. DODDRIDGE.
